UNITED STATES PATENT OFFICE.

FRANK H. QUIMBY, OF TROY, NEW YORK.

INTERNAL-COMBUSTION ENGINE.

1,283,297.

Specification of Letters Patent. Patented Oct. 29, 1918.

Application filed March 7, 1918. Serial No. 221,003.

To all whom it may concern:

Be it known that I, FRANK H. QUIMBY, a citizen of the United States, residing at Troy, in the county of Rensselaer and State 5 of New York, have invented certain new and useful Improvements in Internal-Combustion Engines, of which the following is a specification, reference being had therein to the accompanying drawing.

10 The invention relates to internal combustion engines and has for its object to provide an internal combustion engine, wherein the gaseous mixture from the carbureter will be taken into the engine through the 15 crank casings, thence through passages of the cylinder casings to the intake valves. The intake valves being operated by means of cams carried by a cam shaft, said cams being so disposed that they will engage the 20 ends of the valve stems and force them inwardly against the action of springs, thereby admitting gaseous charges to the combustion chambers of the cylinders of the engine.

25 A further object of the invention is to provide a valve actuating mechanism, wherein the intake valves will be actuated by cams carried by a rotating cam shaft, also to provide means whereby the said cam shaft may be disposed nearer to, or farther away from 30 the ends of the valve stems, thereby allowing, when the cams engage the ends of the valve stems an increased or diminished amount of gaseous mixture to enter the combustion chambers of the cylinders.

35 A further object of the invention is to provide a valve controlled mechanism for internal combustion engines, comprising a shaft, having eccentrics at its ends, said eccentrics being mounted in fixed bearings 40 and a rotatable cam shaft telescopically, but rotatably mounted on the same and connections between the cam shaft and the crank shaft, whereby the cam shaft will be rotated, thereby causing the engagement of the 45 cams with the ends of the valve stems. Also to provide means on the eccentric shaft, whereby the eccentrics may be oscillated in their bearings so that the cams may 50 be brought closer to or farther away, from the ends of the valve stems, so as to increase or diminish the size of the gaseous charge admitted to the cylinders of the engine. It being understood that the location of the 55 valve actuating cams may be varied or changed according to the kind of engine to

which it is applied. For purpose of illustration a four-cycle engine is shown, that is to say, the piston makes four strokes to complete a cycle of operation. However, it 60 is obvious that the mechanism may be applied to other types of engines by changing the location and number of cams.

A further object of the invention is to provide a valve actuating mechanism, which 65 may be easily removed from the engine and the cylinder heads, carrying the valve, removed, so that the tops of the combustion chambers may be inspected or cleaned.

With the above and other objects in view, 70 which will appear as the description proceeds, the invention resides in the details of construction and combination and arrangement of parts hereinafter described and claimed, it being understood that changes 75 in the precise embodiment of the invention herein described may be made within the scope of what is claimed without departing from the spirit of the invention.

Figure 1 is a side elevation of the upper 80 end of a four-cylinder internal combustion engine, showing the valve mechanism applied thereto.

Fig. 2 is a vertical longitudinal sectional view of a portion of the engine and valve 85 mechanism.

Fig. 3 is a vertical sectional view on line 3—3 of Fig. 2, showing the starting of the intake stroke.

Fig. 4 is an enlarged detail view of the 90 valve and actuating mechanism, showing the same in intaking position.

Fig. 5 is an enlarged detail view of the 95 valve mechanism showing the eccentric shaft disposed nearer the ends of the valve stems.

Fig. 6 is a perspective view of the cam sleeve.

Fig. 7 is a perspective view of the eccentric shaft.

Referring to the drawings 1 designates a conventional form of four-cycle engine, which comprises cylinders *a*, *b*, *c*, and *d*. Each cylinder is provided with the usual crank casing 2, said casings are partitioned 105 from each other by walls 3, however, these walls may be eliminated if desired. The crank casings are air tight and are so constructed that they will retain the gaseous mixture when forced therein from the carbureter. The gaseous mixture enters the crank casings through ports 4 in the sides 110

of the cylinders *a*, *b*, *c* and *d*, which communicate with the intake manifold 5, said intake manifold being in turn connected to the carburetor port (not shown) by means of 5 the pipe 6. Threaded into the upper ends of the cylinders as at 7 are cylinder heads 8. The cylinder heads 8 are provided with chambers 9 for the reception of the gaseous mixture from the crank casings 2, which enter the same through the passages 10 formed by the walls 11 of the water cooling jacket 12 of each cylinder. The passages 10 terminate in registration with openings 13 in the walls 14 of the cylinder heads. The upper 10 wall 15 of each cylinder head is provided with upwardly and downwardly extending bosses 16 and 17 forming bearings 18 for the reception of the valve stems 19. The lower walls 20 of the cylinder heads are provided 15 with intake ports 21 in which the valves 22 seat. Threaded to the valve stems 19 are sleeves 23 having enlargements 24, which are provided with annular flanges 25 and between the enlargements 24 and the upper 20 walls 15 of the cylinder heads coil springs 26 are disposed, these coil springs keep the valves normally in engagement with the valve seats 21. Threaded upon the valve stems 19, as at 27 are cam engaging members 25 which comprise internally threaded sleeve portions 29 and enlarged cam engaging portions 30. The springs 26 are of such a tension that they will keep the valves 22 in engagement with their respective valve seats 30 until the valves are forcibly opened, by the valve actuating mechanism.

Secured to the sides of the cylinders *a* and *d* by means of bolts 31 or brackets 32, having bearings 33 in which eccentrics 34 are rockably mounted. The eccentrics 34 are provided with rectangular apertures 35 for the reception of the rectangular ends 36 of the rockable shaft 37, said shaft being provided with bearing enlargements 38 and reduced 40 portions 39. The enlargements 38 are provided with lubricant grooves 40, the ends of the rockable shaft having threaded reduced portions 41, one of said reduced portions being for the reception of a cap plate 42, which is threaded and pinned upon the reduced portion by means of a pin 43, the other reduced portion 41 of the shaft 37 receives the operating arm 44, which is provided with a lug 45 engaging an aperture 46 in the eccentric 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 The invention having been set forth what is claimed as new and useful is:—

1. In an internal combustion engine comprising a cylinder, a cylinder head secured to said cylinder, a valve carried by said cylinder head and normally held closed, a rockable shaft disposed over the ends of the valve stem, a rotatable sleeve telescopically and rotatably mounted upon the rockable shaft and provided with a cam rigidly secured thereto and means whereby the cam may be disposed at different distances from the end of the valve stem.
2. In an internal combustion engine comprising a cylinder, a cylinder head secured to said cylinder, a valve carried by said cylinder head and normally held closed, a rockable shaft disposed over the end of the valve stem and having eccentrics at its ends mounted in stationary bearings, a rotatable sleeve telescopically and rotatably mounted upon the rockable shaft and provided with a rigid
3. In an internal combustion engine comprising a series of cylinders, cylinder heads secured to said cylinders, valves carried by said cylinder heads, a rockable shaft disposed over the valve stems and having eccentrics at its ends mounted in bearings and having reduced portions, a rotatable sleeve telescopically and rotatably mounted upon the rockable shaft, means for rotating the rotatable shaft, cams rigidly secured to the rotatable shaft and means whereby the eccentrics may be rocked in their bearings so that the cams may be disposed at different distances from the valve stems.

In testimony whereof I hereunto affix my signature.

FRANK H. QUIMBY.
